CLOCK WITH DISC INDICATORS

Jules S. Worthington, 812 Chelham Way,
Santa Barbara, Calif. 93103

Filed Jan. 30, 1970, Ser. No. 21,151

Term of patent 14 years

Int. Cl. D10—01

U.S. Cl. D42—7

FIG. 1

FIG. 2

FIG. 3

FIG. 4

FIG. 5

FIG. 1 is a top view of the clock with disc indicators showing my new design;

FIG. 2 is a front elevational view, indicating the time as 12:00;

FIG. 3 is a side elevational view;

FIG. 4 is a front elevational view, indicating the time as 6:00; and

FIG. 5 is a front elevational view; indicating the time as 5 minutes after 9:00.

The drawing is lined to indicate color without reference to specific colors.

I claim:

The ornamental design for a clock with disc indicators, as shown and described.
